UNITED STATES PATENT OFFICE.

WALTER S. MCKEE, OF GLENCOE, ILLINOIS, ASSIGNOR TO EDGAR ALLEN AMERICAN MANGANESE STEEL COMPANY, OF AUGUSTA, MAINE, A CORPORATION OF MAINE.

TWO-PART DIPPER FOR EXCAVATING-MACHINES.

1,077,486.

Specification of Letters Patent.

Patented Nov. 4, 1913.

Application filed June 11, 1912. Serial No. 703,012.

To all whom it may concern:

Be it known that I, WALTER S. MCKEE, a citizen of the United States, and a resident of Glencoe, in the county of Cook and State 5 of Illinois, have made and invented certain new and useful Improvements in Two-Part Dippers for Excavating-Machines, of which the following is a specification.

My invention relates to dippers for excavating, dredging, digging and similar machines, and more particularly to dippers comprising a body portion made up of two parts each formed from cast metal and each forming approximately one-half of the dipper body, the two parts being joined together along joints located in the sides of said body portion.

The objects of my invention are to provide an arrangement of ears through which 10 the dipper is lifted whereby the entire strain, due to lifting the dipper by means of a suitable bail, the lower end of which is connected with the ears, is exerted upon the front portion only of the dipper body; to 15 provide an improved form of joint through which the two parts of the dipper body are secured together; to provide an improved arrangement of bail pins and parts associated therewith through which the lower 20 ends of a lifting bail are secured to the dipper body through the ears aforesaid; and to provide such further improvements in 25 and relating to dippers for excavating machines as are hereinafter more fully and at 30 length described and claimed.

The drawing accompanying and forming a part of this application illustrates the preferred embodiment of my invention, although it will be understood that the same 35 is capable of embodiment in other specific forms and that my invention includes such variations and modifications of the particular form illustrated as will be obvious to those skilled in the art to which my invention relates.

Referring to the drawing: Figure 1 is a view showing a dipper body in perspective, the same being made in accordance with my invention; Fig. 2 is a view somewhat enlarged showing a section upon a transverse plane indicated by the line 2-2, Fig. 1; Fig. 3 is a view showing a section upon a plane including the line 3-3, Fig. 1, looking toward the shoulder of the lifting ear as

indicated by the arrows; and, Fig. 4 is a view showing a bail pin in perspective.

Referring to the drawing, the reference characters 5, 6 designate portions of a two-part dipper body, the same being made from cast metal and preferably from cast manganese steel in order to reduce to a minimum the mechanical processes necessary in forming the dipper and provide a body having the excessive strength and wearing qualities of the preferred material mentioned. The rear ends of the front portion overlap the forward ends of the rear portion as shown, and the two parts are secured together along joints located in the sides of the finished body, whereby a unitary two-part body portion is procured. The forward portion 6 is preferably formed with recesses in its inner surface as shown in Fig. 2, and the outline of which is indicated by the lines 7, Fig. 1, within which the correspondingly shaped forward ends of the rear portion 5 of the body lie; whereby a stronger joint, and a dipper body having a smooth interior surface, are procured. The dipper body will be provided with suitable lugs 8 to which the means for directing the movements of the dipper are connected, a suitable lip 9, and suitable teeth 10, which features, however, form no part of the invention to which this application relates. The two parts of the dipper body are commonly secured together by means of suitable rivets 11 arranged along the joint between the parts.

The dipper body formed as above explained is lifted when the dipper is in use to thereby fill it with the material being operated upon by means of a bail, not shown, the lower ends of which are secured one to each side of the body portion through suitable bail pins, one of which is shown at 12, Fig. 4. The outer ends of these bail pins extend through bearings 13 formed in the upper ends of lifting ears 14, and the inner ends of said pins are supported in bearings 15 formed in the front portion 6 of the dipper body, the rear portion of the body having openings 16 registering with, but larger than the bearings 15 above referred to.

It will be understood that while but a single lifting ear is shown, one will be located upon each side of the dipper body.

The bail pin 12 is commonly provided with an enlarged head 17 which lies within the opening 16 and the head and opening are preferably square as shown. The opening 5 is large enough in the preferred arrangement of the parts to leave a space between its walls and the periphery of the head of the bail pin, so that the inner end of the pin 12 is supported entirely by the bearing 15, 10 which, as above mentioned, is formed in the front portion 6 of the body portion of the dipper.

The base portions 18 of the lifting ears above referred to rest entirely upon the 15 front portion of the two-part dipper body, as shown in Fig. 1, each of which bases abuts against a lug 19 formed integrally with the said front portion, the upper ends of the ears being offset to provide spaces between 20 the lugs and ears within which the lower ends of the lifting bail lie when the parts are assembled; and the ears are secured in place upon the front portion of the dipper body by means of rivets 20 extending 25 through the bases and through the overlapping portions of the two parts of the body, whereby the rivets in addition to securing the ears in place, assist in holding the parts of the body together.

30 In view of the premises it will be appreciated that the lugs 19 serve to relieve the rivets 20 from shearing strains and, the bases 18 and lugs 19 being upon one and the same part of the dipper body, their 35 relation with one another cannot change when the dipper is in use; and the stresses upon the rivets 20 are therefore not subject to changes due to looseness or distortion of the joint between the front and rear portion developing when the dipper is in use as is the case where the ears are secured to one part of the dipper body and the lugs formed upon the other. The bearings 15 for the inner ends of the bail pins being also 40 upon the forward part of the body, it follows that the entire strain due to lifting the dipper is borne by the front of the dipper body, and that the distribution of such strain remains unchanged throughout the 45 life of the dipper and is unaffected by such looseness or distortion as commonly develops at the joint between the two parts of the body portion thereof when the dipper is in use.

50 Having thus described and explained my invention, I claim and desire to secure by Letters Patent:

55 1. In a dipper for excavating and similar machines, a dipper body comprising front and rear portions formed from cast metal and secured together along joints located in the sides thereof to thereby form a two-

part dipper body, the rear ends of said front portion overlapping the forward ends of said rear portion; two lifting ears located 65 one upon each side of the body and the bases of which ears rest entirely upon the front portion of said body, said ears having each a bearing to receive one end of a bail pin and the front portion of said body having bearings located in line with the bearing in said ears; two lugs formed integrally with the front portion of the body and against which the bases of said ears abut; and means for securing said several parts 75 together.

2. In a dipper for excavating and similar machines, a dipper body comprising front and rear portions formed from cast metal and secured together along joints located in 80 the sides thereof to thereby form a two-part dipper body, the rear ends of said front portion overlapping the forward ends of said rear portion; two lifting ears located one upon each side of the body and the bases 85 of which ears rest entirely upon the front portion of said body, said ears having each a bearing to receive one end of a bail pin, the front portion of said body having bearings located in line with the bearings in 90 said ears, and the rear portion of said body having openings in line with and larger than the bearings in said front portion; two lugs formed integrally with the front portion 95 of the body and against which the bases of said ears abut; and means for securing said several parts together.

3. In a dipper for excavating and similar machines, a dipper body comprising front and rear portions formed from cast metal and secured together along joints located in 100 the sides thereof to thereby form a two-part dipper body, the rear ends of said front portion overlapping the forward ends of said rear portion; two lifting ears located one upon each side of the body and the bases of which ears rest entirely upon the front portion of said body; fastening means for securing said ears in place and which fastening means extend through the overlapping 105 parts of the front and rear portions of said body; two lugs formed integrally with the front portion of the body and against which the bases of said ears abut; and fastening means arranged along the joint between said front and rear portions for securing 110 them together.

Signed at Chicago in the county of Cook and State of Illinois this fourth day of June A. D. 1912.

WALTER S. MCKEE.
